CLAIM

The ornamental design for a combined roll of tape and support arm for a tape printer cartridge, as shown and described.

DESCRIPTION

FIG. 1 is a top plan view of a combined roll of tape and support arm for a tape printer cartridge showing my new design;

FIG. 2 is a front elevational view thereof;

FIG. 3 is a bottom plan view thereof;

FIG. 4 is a left side elevational view thereof;

FIG. 5 is a right side elevational view thereof;

FIG. 6 is a rear elevational view thereof; and,

FIG. 7 is a perspective view thereof.
